UNITED STATES PATENT OFFICE

FERDINAND ZOGLAUER, OF PETERSWALDS, NEAR ORLAU, CZECHOSLOVAKIA

ROWING DEVICE

Application filed February 7, 1930. Serial No. 426,722.

My invention relates to new and useful improvements in rowing devices, and has for its object the provision of a device in combination with the oar of a boat which is adapted for imparting a higher speed to the boat or for stopping it in a shorter time than heretofore. In addition to this, the invention comprises means embodying certain other novel features of construction, combination and arrangements of parts substantially as disclosed herein and as illustrated in the accompanying drawings, in which:

Figure 1 is a side elevation of the complete device with the striking blades in operative position,

Figure 2 is a detached view of the oar-swivel, and

Figure 3 is a side elevation of the lower portion of the device with the striking blades in inoperative position, and

Figure 4 is a vertical sectional view as indicated by the line A—B of Figure 3.

In the drawings, the numeral *a* designates the oar proper which is arranged within a steel tube *b* of the shape shown, supported therein by suitable bearings and adapted to be displaced in axial direction. The upper portion of the loom is provided with a spiral spring *c* bearing on the one hand against a knob *d* forming top of the loom and somewhat upstanding from the end of the steel tube, and on the other hand against the bearing flange *e* of the tube, the said spring having the tendency of constantly holding the oar in its normal position. A handle *f* preferably made of ebonite, is fixed to the upper extremity of the loom, but loosely mounted on the tube shaft so that the said handle may be capable of sliding on the said shaft.

The lower portion of the steel tube is provided with a longitudinally extending slot *g* rather broadly dimensioned and allowing the passage of two large striking blades *h* preferably made of sheet steel and hinged to the loom close and in parallel direction to each other. The said blades are therefore capable of swinging about their hinges, and the arrangement is so made that the two metal edgings of the slot *g* form a stop for the

blades when in their open or operative position.

Toward the lower extremity of the steel tube, the slot *g* is followed by another slot *i* being of much smaller dimensions than the first mentioned slot and allowing a partial entering of the front edges of the blades when the oar is being displaced axially, the said slot *i* serving therefore as a retaining device for the blades *h*.

The described device in combination with the oar proper is carried by an oar-swivel *k* in the usual manner.

In operation: In the normal position, the spiral spring *c* holds the blades *h* out of engagement with the slot *i* and rowing may be effected as usual. However, owing to the new arrangement, each stroke of the oar results first in an inoperative action by the two striking blades swinging automatically about their hinges so as to become positioned parallel to each other, in which position they are dividing the water easily and with only a slight resistance; secondly, in the operative action proper in which the two blades, under the pressure of the column of water, are again swinging about their hinges, but in reverse direction so as to form one continuous large surface and to present to the water this large surface, realizing thereby an oar stroke of maximum power and imparting to the boat a much higher speed than heretofore.

When it is desired to change the course of the boat, or to turn round sharply, the rower presses by hand down the knob *d* of the respective oar so as to cause the one loom to be displaced axially and the front edges of the blades *h* to enter the slot *i* in which the said blades remain as long as the knob *d* is held pressed down. As soon as the turned boat is about to continue its course, the rower ceases the pressure exerted on the knob, and the loom under the action of the spring, is brought back to its initial position, withdrawing at the same time the blades *h* from the slot *i*.

The operating mechanism which embodies the essential features described, is so designed as to be applicable to boats and sculls of any kind.

What I claim as new, is:

1. In a rowing device of the character described, the combination with an oar, a steel tube within which the loom of the oar is arranged, means for holding said loom within said steel tube, a handle surrounding the upper end of said tube, and striking blades in connection with the lower end of the said loom.
- 10 2. In a rowing device of the character described, the combination with an oar, a steel tube having at its lower end a longitudinal slot and within which the said oar is slidably arranged a bearing flange on said tube, means for supporting the loom of the oar, an oar-swivel for supporting the loom, a knob fixed on the upper end of the loom projecting from the upper end of said steel tube, a spiral spring arranged round the loom and bearing against said knob and against said bearing flange of said tube, a handle fixed to said knob and loosely surrounding said steel tube, and adapted to be displaced in axial direction together with the loom, striking blades adapted to pass through the longitudinal slot in said tube, hinges in connection with the said striking blades and with the loom of said oar and about which said blades are adapted to swing, and edgings on each side of the slots in said tube adapted to form a stop for said striking blades in their operative position.
- 20 3. In a rowing device of the character described, the combination with an oar, a steel tube having at its lower end a longitudinal slot with an extension of smaller dimensions and within which the loom of the oar is slidably arranged a bearing flange on said tube, means for holding the said loom within said steel tube, an oar-swivel for supporting the loom, a knob fixed to the upper end of said loom and upstanding from the upper end of said steel tube, a spiral spring arranged round the loom of said oar and bearing against said knob and against said bearing flange of said tube, said spring having the tendency of constantly holding said oar in its normal position, a handle fixed to said knob and loosely surrounding said steel tube, and adapted to be displaced in axial direction together with the loom, striking blades of said oar, hinges in connection with said striking blades and with the loom of said oar and about which said striking blades are adapted to swing, edgings on the longitudinal slots of said tube adapted to form a stop for said striking blades in their operative position, the front portions of said striking blades being adapted to engage and be held in position in the narrow extension of the slot in said tube, when said knob is depressed by hand, said oar being displaced axially, and on the pressure on said knob causing said striking blades to be withdrawn from the narrow extension of the slot in said tube and the rowing device to be.
- 25 35 40 45 50 55 60 65 70 75 80 85 90 95 100 105 110 115 120 125 130

brought back to its initial position, under the action of said spring.

In testimony whereof I have affixed my signature.

FERDINAND ZOGLAUER. 70
